UNITED STATES PATENT OFFICE.

JOSEPH LINDBURG, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed October 9, 1925. Serial No. 61,404.

This invention relates to means for facilitating the front insertion of work-sheets in typewriting machines.

When two or more work-sheets are to be inserted around the platen of a typewriting machine, in registering position to each other, it is sometimes desirable to insert one of the sheets from the front of the machine.

10 Various expedients have been resorted to in the past, to facilitate the front insertion of work-sheets, but it has been usually required to rebuild the platen-frame of the machine in order to adapt a regular machine 15 for front insertion. This, of course, is objectionable since it requires special manufacturing equipment which is costly.

One of the features of this invention relates to means whereby a standard machine 20 having an introductory chute or table at the rear of the platen, and having releasable feed-rolls, may be arranged for front introduction of the work-sheet, with little or no alteration thereof.

25 According to this invention, the rear table is slidably mounted upon a cross-bar forming an integral part of the platen-frame, and is connected to the feed-rolls in a manner to displace the table away from the 30 platen when the feed-rolls are released and to move it towards the platen when the feed-rolls are rendered operative. The rear table extends downwardly from its supporting cross-bar and encircles the under side of 35 the platen, the forward end or edge of the table being below the printing point, and is slightly flared out to provide a bell-mouthed opening, between itself and the periphery of the platen, for the trailing edge of the work- 40 sheet. The Underwood standard typewriting machine, in connection with which this invention is illustrated, is provided with front and rear feed-rolls, both being operatively mounted on a shaft underlying the 45 platen. The front rolls are operatively connected to the under side of the table in a manner to slide the table downwardly and forwardly away from the platen when the feed-rolls are released, the table being re-

50 turned to close proximity with the platen when the feed-rolls are rendered operative, thereby providing a guide for the work-sheets.

It will be understood that owing to the 55 extreme simplicity of this device it is feasi-

ble to provide standard typewriting machines with a front as well as a rear insertion for the work-sheet, thereby rendering the machine more flexible and adaptable to different classes of work without noticeably 60 increasing the manufacturing cost thereof.

Other features and advantages will hereinafter appear.

In the accompanying drawings,

Figure 1 is a front view, in elevation, of 65 the platen-frame of an Underwood standard typewriting machine having the invention applied thereto.

Figure 2 is a side view, in elevation, showing the feed-rolls and the rear table in effective position.

Figure 3 is a side view, in elevation, showing the feed-rolls and the table in a released position, the work-sheet being introduced 70 at the front of the platen.

75 The Underwood standard typewriting machine has a platen 10, revolvably mounted upon end plates 11 of a platen-frame, borne by a carriage, not shown. The end plates 11 are connected together, so as to form a 80 rigid frame, by means of a tie-rod 12 and a cross-bar 13, the latter being secured to the end plates by means of rivets 14.

85 It has been customary to provide said Underwood machine with feed-rolls 15 and 16, operatively mounted upon the rod 12, and held in engagement with the platen 10 by means of springs 17 actuating on tabs 18 and 19, the latter forming an integral part 90 of supporting pieces 19^a, secured to the rod 12, while the former are bent out of the arms 20 and 21, in which feed-roll-shafts 22 are journaled. Said feed-rolls are releasable by means of a manually-operable lever 23, pivotally mounted upon a stud 24 and 95 operatively connected to an operating shaft 25 by means of a link 26 and an arm 27, forming an integral part of said shaft 25, in a manner disclosed in the patent to W. F. Helmond, No. 1,392,940, dated October 11, 100 1921.

105 In order to facilitate the front insertion of the work-sheet around the platen, a rear table 28, which serves as a chute for the work-sheet at the introductory side of the platen, is extended downwardly and forwardly, and then under the platen in close proximity thereto, and terminates with a flared-out edge 29 below the printing point 110 in front of a guide 30 for types 31. The

table is slidably mounted upon the cross-bar 13, which is provided with studs 32 fast thereto, the upper ends of the studs being turned down to engage with elongated slots 5 33 in the table, and the table being held in sliding relationship with the studs by means of screws 34. Since it is desired to simultaneously separate the portion underlying the platen from the platen itself, and 10 to release the feed-rolls preparatory to inserting a work-sheet in front of the platen, it has been found advantageous to control the movement of the table by the front arms 20 of the front feed-rolls, and to this end, 15 there are provided clips 35, fast to the under side of the table, the clips being provided with hooks 36, designed to engage with the arms 20 in a manner to draw on the table when the feed-rolls are swung to ineffective 20 position, as shown in Figure 3.

The work-sheet is inserted at the front of the platen, as shown in Figure 3, whereupon the feed-rolls are again restored to their normal position, and the platen is rotated 25 backwardly by means of a finger-wheel 37, fast to the platen-axle 38. In order to forcibly restore the table to its normal position when the feed-rolls are restored, the feed-rolls are arranged to protrude through openings 39 in the table, to engage with the platen, and the feed-roll-shafts are provided 30 with rollers 40, and 41, respectively, on the front and rear feed-roll-shafts, which rollers engage with the under side of the table and 35 force it upwardly and rearwardly to a position as shown in Figure 2.

Variations may be resorted to within the scope of the invention, and portions of the improvements may be used without others.

Having thus described my invention, I claim:

1. The combination with a front-strike typewriting machine having a revoluble platen and releasable feed-rolls therefor, of 45 a chute or table at the introductory side of the platen for conducting a work-sheet to the feed-rolls, said table being slidably mounted upon a stationary member and extending forwardly and downwardly, and 50 then under the platen in close proximity thereto, and terminating with a flared-out edge below the printing line, means controlled by the feed-rolls to concomitantly move the underlying portion of the table 55 away from the platen when the feed-rolls are released, so as to form an opening between the flared-out edge of the table and the periphery of the platen, and means for restoring the position of the table when the 60 feed-rolls are moved to their effective positions.

2. The combination with a typewriting machine having a platen revolubly mounted upon a platen-frame, a cross-bar for stiffening the end plates of said frame, feed-rolls

co-operating with said platen to feed work-sheets therearound, said feed-rolls being rotatably mounted upon arms, the arms, in turn, being rockably mounted upon a shaft connecting said end plates, means for resiliently holding the feed-rolls in engagement with the periphery of the platen, and means for manually rendering the feed-rolls ineffective, of a rear table slidably mounted upon said cross-bar and extending downwardly and forwardly under and around the platen, between the platen and the feed-rolls, the latter protruding through openings in the table to engage the platen, and the table terminating with a flared-out edge 70 forming an elongated opening for the work-sheet, between itself and the periphery of the platen, and means controlled by the feed-rolls effective to slide the table downwardly 75 and forwardly, away from the platen when the feed-rolls are released, and to conversely move the table rearwardly and upwardly toward the platen and in close proximity thereto when the feed-rolls are rendered operative. 80

3. The combination with a typewriting machine having a platen revolubly mounted upon a platen-frame, a cross-bar for stiffening the end plates of said frame, feed-rolls co-operating with said platen to feed work-sheets therearound, said feed-rolls being rotatably mounted upon arms, the arms, in turn, being rockably mounted upon a shaft connecting said end plates, means for resiliently holding the feed-rolls in engagement with the periphery of the platen, and means 90 for manually rendering the feed-rolls ineffective, of a rear table slidably mounted upon said cross-bar and extending downwardly and forwardly under and around the platen, between the platen and the feed-rolls, the latter protruding through openings in the table to engage the platen, and the table terminating with a flared-out edge 95 forming an elongated opening for the work-sheets, between itself and the periphery of the platen, and means controlled by the feed-rolls effective to slide the table downwardly and forwardly, away from the platen when the feed-rolls are released, and to conversely move the table rearwardly and upwardly toward the platen and in close proximity thereto, when the feed-rolls are rendered operative, said last-mentioned means including 100 clips fast to the under side of the table and having hooks designed to engage with the arms upon which the feed-rolls are journaled, and rollers rotatably mounted on the feed-roll-shafts and adjacent the feed-rolls, said rollers being of smaller diameter than the feed-rolls and engaging with the under side 110 of said table. 115

4. The combination with a typewriting machine having a platen revolubly mounted upon a platen-frame, a cross-bar for stiffen- 120

- ing the end plates of said frame, feed-rolls co-operating with said platen to feed work-sheets therearound, said feed-rolls being rotatably mounted upon arms, the arms, in 5 turn, being rockably mounted upon a shaft connecting said end plates, means for resiliently holding the feed-rolls in engagement with the periphery of the platen, and means for manually rendering the feed-rolls ineffective, of a rear table slidably mounted upon studs fast to said cross-bar, the table having elongated slots designed to engage with reduced portions of said studs, and screws for holding the table in sliding relationship with the studs, said table extending 10 forwardly and downwardly, under and around the platen below the printing line thereof, and having a flared edge forming a receiving opening for the work-sheets, between itself and the periphery of the platen, and means operatively connecting the table to the feed-rolls in a manner to afford the movement of the table away from the platen when the feed-rolls are released, and toward 15 the platen, in close proximity thereto, when the feed-rolls are rendered operative.
5. In combination with a typewriting machine, a revolute platen journaled in end plates, of a platen-frame, a cross-bar at the rear of the platen for stiffening said frame, a rear table slidably mounted on said cross-bar, said rear table extending downwardly and forwardly from said bar toward the platen in a line substantially tangent to the 20 periphery of the platen and extending under and around the platen, in close proximity thereto, and terminating with a flared-out edge below the printing line of the platen, manually-releasable feed-rolls under said platen and co-operating therewith to feed a work-sheet therearound, and means operatively connecting said feed-rolls to said table in a manner to afford the displacement of the table away from the platen when the 25 feed-rolls are released, and toward the platen when the feed-rolls are rendered operative.
6. In combination with a typewriting machine, a revolute platen journaled in end plates, of a platen-frame, a cross-bar at the rear of the platen for stiffening said frame, a rear table slidably mounted on said cross- 30 bar, said rear table extending downwardly and forwardly from said bar toward the platen in a line substantially tangent to the periphery of the platen and extending under and around the platen, in close proximity thereto, and terminating with a flared-out edge below the printing line of the platen, so as to provide a reception opening for the trailing edge of a frontly-inserted work-sheet, feed-rolls co-operating with the platen to feed the work-sheet therearound, and means for moving the feed-rolls away from the periphery of the platen, said means being also effective to concomitantly move the table away from the platen when the feed-rolls are so moved, and conversely move the table toward the platen when the feed-rolls are thrown in contact with the periphery of the platen. 35
7. In combination with a typewriting machine, a revolute platen journaled in end plates, of a platen-frame, a cross-bar at the rear of the platen for stiffening said frame, a rear table slidably mounted on said cross-bar, said rear table extending downwardly and forwardly from said bar toward the platen in a line substantially tangent to the periphery of the platen and extending under and around the platen, in close proximity thereto, and terminating with a flared-out edge below the printing line of the platen, so as to provide a reception opening for the trailing edge of a frontly-inserted work-sheet, feed-rolls co-operating with the platen to feed the work-sheet therearound, and means for moving the feed-rolls away from the periphery of the platen, said means being also effective to concomitantly move the table away from the platen when the feed-rolls are so moved, and conversely move the table toward the platen when the feed-rolls are thrown in contact with the periphery of the platen, said last-mentioned means including clips fast to the table and engaging with feed-roll-operating arms, and rollers adjacent the feed-rolls, said rollers engaging with the under side of the table in a manner to afford the upward movement of the table when the feed-rolls are thrown to effective position. 40

JOSEPH LINDBURG.
